UNITED STATES PATENT OFFICE.

NEWELL P. COWELL, OF CLEVELAND, OHIO.

VESTIBULE-CAR.

SPECIFICATION forming part of Letters Patent No. 394,840, dated December 11, 1888.

Application filed April 21, 1888. Serial No. 271,385. (No model.)

To all whom it may concern:

Be it known that I, NEWELL P. COWELL, of Cleveland, in the county of Cuyahoga and State of Ohio, have invented certain new and 5 useful Improvements in Vestibule-Cars; and I do hereby declare the following to be a full, clear, and exact description of the invention, such as will enable others skilled in the art to which it pertains to make and use the same.

10 My invention relates to improvements in vestibule-cars, in which an open self-adjusting metal frame is located at the end opening of the vestibule in position to abut a similar frame of an opposing car, such frame being 15 integral with or attached to a deep rim or flange that extends toward the vestibule for closing the space between the frame and vestibule, the internal dimensions of the frame and rim being such as to inclose the passage- 20 way from vestibule to vestibule, said frame being pivoted top and bottom to spring-actuated push-bars, the latter extending lengthwise of the car, by means of which opposing frames are held in contact and the frame may 25 turn on its axis the limited distance necessary to accommodate itself to the curvature of the track, to the end that a substantial enclosure is had of the passage-way from one vestibule to another, whereby the heat of the 30 cars is retained, smoke and dust are excluded, and such passage-way is rendered as safe as other parts of the car.

My invention also relates to details of construction hereinafter described, and pointed 35 out in the claims.

In the accompanying drawings, Figure 1 is a side elevation of a portion of two opposing vestibule-cars. Fig. 2 is a side elevation in section. Fig. 3 is a horizontal section in detail, hereinafter described. Fig. 4 is an end elevation. Fig. 5 is a plan, partly in section. Fig. 6 is a plan showing a portion of two cars in position on a sharp curve of the track.

A represents a vestibule-car.

B is a metal frame, located at the outer end of the vestibule in position to abut a similar frame of an opposing car when the cars are coupled. The internal dimensions of this frame correspond substantially with the inner casing of the vestibule, so that an unobstructed passage-way is had from one car to

another through the opening of these frames. The lower member of the frame has flanges B' and B² for embracing the bumper-plate A', the top surface of flange B' being about 55 flush with the floor a of the vestibule. A thin metal plate, a', is fastened to the floor and overlaps some little distance flange B', so as to cover the crack between the floor and flange. Frame B is provided top and bottom 60 with pivotal pins b and b', that connect, respectively, with spring-actuated push-bars C and C', both extending lengthwise of the car. Each push-bar has a collar, c, held rigid on the push-bar, and a spring, c', engaging such 65 collar, these springs acting outward on the push-bar serve to keep frames B of opposing cars always in close contact so long as the cars are coupled. Push-bar C passes with an easy fit through a hole in the stationary plate 70 D, this plate serving as an abutment for the inner end of the upper spring. The upper end of frame B moves easily, and therefore the upper spring need be of only moderate strength. The lower end of this frame, by 75 reason of the weight thereof, requires more force to move it, and therefore the lower spring is made stronger than the upper spring; also, plate D', against which the lower spring abuts, is movable and is actuated through the 80 medium of a toggle-joint by the draw-bar to give greater tension to this spring when excessive draft is had on the draw-bar, such excessive draft of course tending to separate the cars. The lower push-bar passes with an easy 85 fit through a hole in plate D', and the latter has laterally-projecting lugs d, that operate in grooves d' of plates d', these latter being fastened to the frame-work of the platform. Plate D' is pivotally connected with links E, 90 that in turn are pivoted to lever E'. The latter is pivoted at e to an attachment of the car-sill, and the free end of the lever rests on incline f of draw-bar F, the normal position of these parts when the cars are coupled being approximately shown in Fig. 2. The links and lever form a toggle-joint, and when the draw-bar is drawn outward the incline f raises the free end of lever E', thereby more or less straightening the toggle-joint and causing 95 plate D' to move outward and compress or give greater tension to the engaging spring.

In starting a train the draft on the draw-bar is sometimes excessive, thereby quickly separating the cars some distance farther than the cars are separated when the train is in motion; 5 hence the necessity of giving greater tension to the lower spring corresponding with the extra draft on the draw-bar to insure the lower portion of opposing frames B being kept in firm contact. Each push-bar is provided with a laterally-projecting pin, d^3 , that, 10 by engaging, respectively, plates D and D', limit the outward movement of the push-bars and connected frame. Flange B' extends around the four sides of frame B, forming a 15 deep inclosing-rim that overlaps the inner surface of the vestibule-casing even when the flange is drawn out to its full limit, and consequently this rim always closes the space between frame B and the vestibule. The sides 20 of this rim are preferably concentric with the axis of frame B. So-called "chafing-strips" G are set in vertical pockets of the wood-work, so as to move laterally, these chafing-strips having curved faces to fit the sides of rim B'. 25 Springs g press the chafing-strips against rim B', the latter having sunken panels on the outer surface thereof, b², by means of which the chafing-strips do not rub the parts of rim B that are exposed to view from the outside 30 of the cars, and consequently such exposed portions of the rim may be plates or otherwise ornamentally finished. When frame B is forced back, the chafing-strips are by their engagement with rim B' forced farther apart, 35 but always make tight joints with the rim, and at any time and in any position of the frame and rim in their movements lengthwise of the car the frame and rim may turn on their common axis to accommodate themselves to an opposing frame in passing around 40 curves of a track. (See Fig. 6.)

The frame-work of the vestibule, according to its functions, is intended to be as strong as

other portions of the car, and with my improved devices attached the passage-way from 45 one car to another is rendered as safe as other portions of the cars, and passengers, for instance, in passing to and from the dining-room car are no more exposed to danger or to 50 drafts of air, or inconvenience of any kind, than in passing along the aisles in a body of a car.

What I claim is—

1. In a vestibule-car, the combination, with 55 open self-adjusting rectangular metal frame, of rigid rim or flange connected with such frame and extending toward the vestibule for closing the space between the frame and vestibule, substantially as set forth.

2. In a vestibule-car, the combination, with 60 self-adjusting open rectangular frame, of a rigid rim or flange connected with such frame and projecting toward the vestibule, the sides of such rim being concentric with the axis of the frame, substantially as set forth. 65

3. In a vestibule-car, the combination, with 70 open frame and rim, the latter extending toward the vestibule, of spring-actuated chafing-strips adapted to engage the sides of such rim to form a tight joint therewith, substantially as set forth.

4. In a vestibule-car, the combination, with 75 open self-adjusting frame and inclosing-rim, and chafing-strips for engaging such rim, substantially as indicated, of sunken panels on the sides of such rim, substantially as described, whereby the exposed portions of the rim are not engaged by the chafing-strips.

In testimony whereof I sign this specification, in the presence of two witnesses, this 80 11th day of February, 1888.

NEWELL P. COWELL.
